Charles Wright.

United States Patent Office.

JOSHUA BROOKS, OF BOSTON, MASSACHUSETTS, ASSIGNOR TO HIMSELF
AND BENJAMIN E. CORLEW, OF SAME PLACE.

Letters Patent No. 97,756, dated December 14, 1869; antedated December 1, 1869.

IMPROVEMENT IN ELECTRO-MAGNETIC ADVERTISING-FRAME.

The Schedule referred to in these Letters Patent and making part of the same.

To all whom it may concern:

Be it known that I, JOSHUA BROOKS, of Boston, in the county of Suffolk, and State of Massachusetts, have invented a new and useful Automatic Electro-Magnetic Advertising-Case, of which the following is a full, clear, and exact description, reference being had to the accompanying drawings, making a part of this specification, in which—

Figure 1 represents an elevation of the case embodying my invention.

Figure 2 is a vertical transverse section of the same.

The same letters refer to the same parts in the different figures.

The object of my invention is to produce an advertising or show-case, for the purpose of bringing business-cards or samples, in a novel and prominent way, before the public, and thus call attention to the same; further, to present to view a large number of advertising-cards successively, and yet occupying but very little space compared with the mode of exhibiting show or advertising-cards in inconveniently large frames, thus enabling the observer to have the cards pass by his sight without changing his position, or even the direction of his eyes; and

My invention consists in rolling up and unrolling upon two rollers, alternately, a large band, of paper or other material, to which is attached a number of advertising or business-cards, said rollers to be set in motion by means of an electro-magnetic apparatus, or other motive-power, as gravity or elasticity.

To facilitate the understanding of this apparatus, I will divide the same into three different distinct operations which it performs, and describe it in that order:

First, the working of the electro-magnets;

Second, the manner of revolving the drums which move the band along; and

Third, the releasing of the drums, and the reversing of their motions.

Referring to the drawings—

A is a closed case, the front side of which is covered by a glass.

In the lower portion of case A is placed the battery B, from which conductors *x* and *y*, charged with the opposing currents, are led to a platform containing the two insulators *a* *a'*, upon which plays the armature C, vibrating from or toward the magnets D *D'* and E *E'*, which may be operated in the usual manner.

This forms the first operation.

The second is accomplished by means of links *d* *d'*, attached, at one end, to an arm of armature C, and with the other acting upon bell-crank *e* *f*, *e'* *f'*, pawls *g* *g'*, ratchets *h* *h'*, to which the drums H *H'* are firmly attached, respectively.

When one of the pawls *g* is in contact with the ratchet, it will rotate the latter with drum H, and, therefore, roll up the band on the latter, while, at the same time, the pawl *g'* is thrown off the ratchet, and thus the drum H' is free to pay out the band.

To regulate the motions of the free rollers, a tension is applied to the rims F' F of the drums by means of springs R R.

The third operation, performing the reverse motion of the band *o*, is effected in the following manner:

The band *o* is attached to drums H' H by means of straps *q*, provided with studs *p*', in such a manner, that when the band *o* is wound around the drum, the stud *p*' will fit into a recess of drums H' H, and not present any obstacle in the winding of the band; but, when the band is payed out, the stud will also be drawn out to the extent of strap *q*, and push against arm *m'* of a bell-crank lever, thus throwing up the other, *l*, and, with it, the bar *v*.

The upper end of bar *v* is bent, or provided with a pin, so as to hold the wire *s* of balance-ball *t*, forming a part of pawl *f'*, in the position out of gear of the ratchet *h'*; but, by the upward motion of bar *v*, the balance-weight *i* will be released, and, dropping downward, brings pawl *f'* in contact with ratchet, while, at the same time, by substantially like arrangements, the pawl *f'* is thrown off the ratchet. Therefore, the drum H' will be set in motion in an opposite direction, and drum H, released from the action of pawl *f*, is allowed to pay out the band *o* in the reversed motion.

To use the whole length of the case, the band may be girded over rollers *n* *n'*.

Thus, it will be seen that the band provided with cards will pass down until drum H' has payed out the whole length of the same, when, by a simple automatic operation, the motion is reversed, and the band drawn upward; and this operation will be continued as long as the battery is active.

What I claim as new, and desire to secure by Letters Patent, is—

1. Drums H H', ratchets *h* *h'*, pawls *g* *g'*, bell-crank *e* *f*, *e'* *f'*, and bars *d* *d'*, in combination with an electro-magnetic apparatus, substantially as described.

2. Drum H, strap *q*, stud *p*', in combination with bell-crank lever *m'* *l*, rod *v*, wire *s*, ball *i*, and pawl *g*, substantially as described.

In testimony whereof, I have signed my name to this specification, in the presence of two subscribing witnesses.

JOSHUA BROOKS.

Witnesses:

CARROLL D. WRIGHT,
AUSTIN S. HOWARTH.
